UNITED STATES PATENT OFFICE.

ABEL HENNING, OF OAKLAND, ASSIGNOR, BY DIRECT AND MESNE ASSIGNMENTS, OF ONE-HALF TO ALFRED M. BELT, OF ALAMEDA, AND THOMAS FLINT, OF SAN JUAN, CALIFORNIA.

OIL-GAS APPARATUS.

SPECIFICATION forming part of Letters Patent No. 416,609, dated December 3, 1889.

Application filed June 14, 1888. Serial No. 277,147. (No model.)

To all whom it may concern:

Be it known that I, ABEL HENNING, of Oakland, Alameda county, State of California, have invented an Improvement in Oil-Gas Apparatus; and I hereby declare the following to be a full, clear, and exact description of the same.

My invention relates to an improved apparatus for the manufacture of gas from naphtha or other similar hydrocarbon product.

It consists in certain details of construction, all of which will be more fully explained by reference to the accompanying drawings, in which—

Figure 1 is a longitudinal vertical section of my apparatus. Fig. 2 is a transverse vertical section of the same, taken through the retorts and heating-furnace.

A is the bench or casing for retorts, of which three are shown in the present case, the two retorts B receiving the naphtha or other light hydrocarbon product through the pipe D from an elevated reservoir, and the retort C being situated above the two retorts B, so that the gas formed in B will be delivered into C through pipes E.

F is a furnace, from which the retorts are heated. This furnace is supplied with petroleum or other inflammable liquid through the pipe G, having an injector-nozzle H.

I is a pipe surrounding the injector-nozzle, into which steam is received through the pipe J from the boiler K, and the combined steam and petroleum are injected into the furnace through the nozzle. (Shown at L.)

Water to supply the boiler K is delivered to it through the pipe M. The three pipes D, G, and M receive their supply from the tanks N, O, and P, respectively. The supply of naphtha or hydrocarbon liquid to the retorts is controlled by a valve Q, operated by a valve-stem from the lever R, which is fulcrumed on the post S. The opposite end of this lever is connected by a link with the vertically-moving bellows T, so that when the bellows closes the valve Q is opened, and when the bellows is expanded by pressure this valve will be closed, so as to cut off the supply of naphtha. It will be manifest that

a piston moving in a cylinder would be equally effective to actuate the valve.

U is a gasometer rising and falling in the tank V, having the usual guides and counterweights.

The gas after being made in the retorts is led to the gasometer as follows: Leaving the upper retort C, it passes through the pipe W, which delivers it into the washing-chamber X, which contains water. A series of partitions Y overlap each other, arising alternately from the bottom and depending from the top of the washing-chamber, so as to form a sinuous passage through which the gas passes, and is brought into contact with the water so as to clear it of any solid carbon or other matter which can be taken up or arrested by the water. From the washing-chamber X the gas passes through the pipe Z, and is discharged by a nozzle a into an open pipe b, which leads directly to the inlet-pipe c, opening into the gas-holder. The meeting ends of the nozzle a and the pipe b are slightly separated from each other, and are inclosed in a casing d, which has a pipe e leading into its lower side, through which air is admitted.

f is a valve opening inwardly, through which air is admitted to the pipe e and thence into the chamber d, where it is mixed with the gas arriving from the retort, and forced with it by the discharge from the nozzle a into the pipe d, so as to be carried into the gasometer U. If it is desired to use more of the gas and less of the air, it is done by opening the cock g in the by-pass pipe h, which leads the gas around the chamber d and directly into the pipe b without any admixture of air.

i is a drip-tank into which the condensations from the pipes b and c may be deposited as they accumulate, and j is a pipe through which the condensed deposit may be pumped out from the tank i from time to time, as may be needed. The outlet-pipe k also has an opening or branch into this drip-tank, the gas being prevented from escaping in this direction, however, by means of a partition l, which dips into the water or liquid contained in the drip-tank.

m is a pipe leading from the pipe *b* upward into the bellows *T*.

n is a cock which when open allows gas under pressure from the supply-pipe *b* to enter 5 the bellows *T*, thus expanding it, and through it operating the lever *R* to close the naphtha-supply valve *Q*. This valve *n* is opened by means of a lever-arm *o*, which is engaged by the projection *p* on the side of the gasometer *U*.

When the gasometer rises, the projection *p* engages the lever *o* and turns it sufficiently to open the cock *n* and allow gas to pass into the bellows *T*, with the result above described.

15 The supply being cut off from the retorts, the quantity of gas delivered to the gasometer will soon be diminished, and the latter will sink by reason of the gas being discharged from it more rapidly than it is delivered into it. As it sinks, the spring *r*, pulling on the lever *o*, closes the valve *n*, and thus prevents further admission of gas into the bellows *T*. As the gasometer continues to sink in its tank, the projection *p* engages the lever-arm 25 *s*, and through it operates the cock *t* in the pipe *u*. This pipe *u* leads from the pipe *m*, being connected with it at the point above the cock *n*, so that when the valve *t* is opened, the gas within the bellows *T* will escape, passing 30 through the pipe *m*, pipe *u*, and the valve *t*, which allows the upper part of the bellows to close down by gravitation, it being weighted sufficiently for this purpose.

When the bellows closes, the lever *R* acts 35 to open the valve *Q* and again admit naphtha to flow into the retorts, which it does by gravitation, and gas will again commence to form and be delivered into the gasometer, thus raising it again. The valve *t* is closed 40 as soon as the gasometer commences to rise by the action of the spring *v* upon the lever *s*, which controls the valve, this lever being released from the pressure of the lug or arm *p* as soon as the gasometer rises. By this device I have an automatic control over the 45 supply of gas-making material, so that the apparatus will be self-operative and self-regulating.

Having thus described my invention, what I 50 claim as new, and desire to secure by Letters Patent, is—

1. In a gas apparatus, a retort adapted to vaporize hydrocarbon oil, a tank with a pipe leading therefrom to the retort, a valve adapted to control the passage of oil from said tank, a gasometer, and a pipe connecting the retort with the gasometer and adapted to deliver gas thereto, in combination with a chamber of variable capacity, a pipe connecting said chamber with the gasometer, a lever, one end of which is so connected with the movable side of said chamber and the other with the stem of the valve which controls the retort-supply as to open or close said valve as the chamber contracts or expands, a valve in the pipe from the gasometer to the chamber of variable capacity, a pipe leading from this pipe between said valve and chamber, a valve in said second pipe, arms or levers attached to said valves, and an arm on the gasometer adapted to engage and operate said valves, substantially as described.

2. In a gas apparatus, a retort adapted to vaporize hydrocarbon oil, a tank with a pipe leading therefrom to the retort, a valve adapted to control the passage of oil from said tank, a gasometer, and a pipe connecting the retort with the gasometer and adapted to deliver gas thereto, in combination with a chamber of variable capacity, a pipe connecting 80 said chamber with the gasometer, a lever one end of which is so connected with the movable side of said chamber and the other with the stem of the valve which controls the retort-supply as to open and close said 85 valve as the chamber contracts or expands, a valve in the pipe from the gasometer to the chamber of variable capacity, a pipe leading from this pipe between said valve and chamber, a valve in said second pipe, arms or levers attached to said valves, an arm on the gasometer adapted to engage and open said 90 valves, and springs adapted to close said valves when released from the arm on the gasometer, substantially as described.

In witness whereof I have hereunto set my hand.

ABEL HENNING.
